UNITED STATES PATENT OFFICE.

PETER J. BURKE, OF MESHANTICUT PARK, RHODE ISLAND, ASSIGNOR TO ATLANTIC TUBING COMPANY, OF PROVIDENCE, RHODE ISLAND.

DEVICE FOR FORMING COUPLING ENDS FOR GAS AND FLEXIBLE METAL TUBING.

1,426,037.

Specification of Letters Patent. Patented Aug. 15, 1922.

Application filed March 7, 1921. Serial No. 450,506.

To all whom it may concern:

Be it known that I, PETER J. BURKE, a citizen of the United States, residing at Meshanticut Park, in the county of Providence and State of Rhode Island, have invented new and useful Improvements in a Device for Forming Coupling Ends for Gas and Flexible Metal Tubing, of which the following is a specification.

10 This invention relates to certain new and useful improvements in a device for forming coupling ends for gas and flexible metal tubing, and it has for its primary object to provide a simple mechanism having a single 15 means of control for the combined operation of clamping, cutting or severing, and discharging or dislodging the tube.

The invention consists in a tube holder embodying a clutch, a stop arranged beyond 20 the latter for gaging the length of tube to be severed, a withdrawable support or tail stock associated with the stop to support the free end of the fed tube, a cutter arranged in proximity to the chuck to sever the 25 desired length of tube, a dislodging member functioning subsequent to the severance of the tube length, and a simplified means of control whereby upon operation in one direction the clutch, cutter and tail stock will 30 be brought into play and upon a reversal of the control means these elements will be rendered inoperative and the dislodging member will function to positively remove the severed tube from the machine.

35 The invention further consists and resides in the features of construction and the arrangements and combinations of parts herein described in detail and succinctly claimed, reference being had to the accompanying 40 drawings wherein

Figure 1 is a top plan view of the improved machine or device;

Figure 2 is a vertical section therethrough on line 2—2 of Figure 1;

45 Figure 3 is a fragmentary sectional view similar to Figure 2 but showing the tube clutch inoperative;

Figure 4 is an end elevation of the clutch;

Figure 5 is an elevation of the cutter, dislodger and control means therefor, a portion 50 of the tail stock operating means also being shown;

Figure 6 is a side elevation of the tail

stock and its associated parts, a portion being broken away; and

Figure 7 is a side elevation of a coupling end, the dotted showing being that of the stock from which the end has been severed. 55

Referring in detail to the drawings, to the bed of the machine are secured the standards 2 having journal bearings 3 for the hollow chuck support 4 which is retained against lengthwise movement by collars 5 60 impinged against the opposite sides of one bearing 3 and which carries on its free inner end the chuck jaws 6 and the jaw-closing cam-sleeve 7, said sleeve having lengthwise movement imparted thereto through means 65 of the yoke 8 engaged in a peripheral groove, as shown. A feed tube or guide 9 is fixed to the companion bearing 3 by screws 10 and has guide extensions projecting inwardly into the chuck support. A pulley 70 11 fixed on the chuck support intermediate the journal bearings derives its power from a suitable source for rotating the chuck and its clamped tube. Obviously, if the chuck is inoperative it will merely slip about the 75 tube since the latter is supported throughout the major portion of its length by the fixed extensions of guide 9.

The tail stock comprises a base 12 surmounted by a sectional and adjustable arm 13 to which is secured a center support 14, the same having a longitudinal slot 15 through which the bolt or screw 16 passes in securing the support to the arm for adjustment. The support has its end upturned to 80 provide alined bearings for the center 17 to slide in, the forward bearing constituting a stop against which the tube is moved to determine the length to be severed from the stock. The length may be varied by effecting adjustment of the support 14. The center is normally projected to receive and support the tube, and overlying the projected end of the center is a rounded, hook-shaped 85 dislodging member 18 which is pivoted to 90 the base at 19.

A cutter 20 is removably secured in a holder 21 on the inner end of a slidale bar 22, the same being mounted in bearings 23 on the base and pivotally connected to the 100 upper portion of a vertical lever 24 which constitutes the single control for the cutter, chuck, center or tail stock and the dislodger.

The cutter and its support are mounted for movement at an angle whereby the cut produced on the length of tube will provide a tapered end 25 and a flared end 26, Figure 7, 5 the tapering cut being simultaneously formed with the formation of the flared cut on the next succeeding length of tube.

A bell crank lever 27 is pivoted to the base 12 and has one arm connected to an 10 arm 28 carried by the bar 22 and the free ends of the two parallel members comprising the companion arm provided with a set screw 29 designed to engage the yoke 8 and shift the cam sleeve 7 to effect clutching of 15 the tube. A second bar 30 is pivotally connected to the lever control 24, and has pivotally connected therewith an arm 31 which is carried on one end of a flexible shaft 32 while the opposite end of the latter is also 20 provided with an arm 33 that has linked connection with a collar 34 fixed to the center 17. Consequently, rocking of the arm 31 will effect sliding of the center. The dislodger 18 is shaped to provide a cam portion 35 on which rides a pin 36 carried by the slide bar 30, whereby upon outward movement of the lever the pin will depress the dislodger to remove the severed tube 25 from the center and the chuck in the event it has a tendency to stick or remain on the center.

In operation the tube is fed manually through the guide 9 and chuck until it is arrested by contacting with the stop of gage 33 member 37 on the forward end of the support 14. The control lever is then swung inwardly, or to the full lined position of Figure 5, which movement performs the following operations, namely, clutches the 40 tube to firmly hold it and also to impart rotary motion thereto, shifts the cutter in against the tube, and slides the center farther into the tube to provide a substantial support therefor during the cutting operation. The length of tube having been severed to produce the finished coupling end article, the control lever 24 is swung outwardly being limited by the right angular stop 38, which action releases pressure on the 45 clutch sleeve, retracts the cutter, withdraws the center so that the coupling end or length of tube may drop from the machine, and depresses the dislodger 18 which functions to positively dislodge the length from the center or chuck in the event the same becomes caught.

It will be noted that the single lever 24 constitutes the sole means of control and by it the complete cycle of operations is effected. While the operator is actuating the lever with one hand he may be feeding the tube with the other and thus expeditiously sever the tube stock into the finished products without the exercise of great physical 60 effort or the provision of heavy machinery.

The tube lengths are produced ready for attachment to the ends of gas tubing or flexible metallic tubing, and do not require further finishing. The dislodger will be returned to its normal position by means of 70 spring, not shown.

Having thus described my invention, what I claim as new and desire to secure by Letters Patent is:—

1. A machine for forming coupling ends 75 for flexible tubing, comprising a stationary tube guide, a rotary chuck having a rearward hollow support journaled for rotation about the guide, the latter having a stationary extension into the hollow support, a cutter mounted for movement toward and from the chuck to sever the projecting end of the tube, and a single means of control for operating the chuck and the cutter. 80

2. A machine for forming coupling ends for flexible tubing, comprising a stationary tube guide, a rotary chuck having a rearward hollow support journaled for rotation about the guide, the latter having a stationary extension into the hollow support, a cutter mounted for movement toward and from the chuck to sever the projecting end of the tube, a tail stock adjustable to constitute a gage stop for the tube as fed from 90 the chuck, a center movably carried by the tail stock toward and from the chuck for entering the tube to support the projecting end thereof, and a single means of control for the chuck, the cutter and the center. 95

3. A machine for forming coupling ends for flexible tubing, comprising a stationary tube guide, a rotary chuck having a rearward hollow support journaled for rotation about the guide, the latter having a stationary extension into the hollow support, a cutter mounted for movement toward and from the chuck to sever the projecting end of the tube, a tail stock adjustable to constitute a gage stop for the tube as fed from 100 the chuck, a center movably carried by the tail stock toward and from the chuck for entering the tube to support the projecting end thereof, a dislodging member operable to remove the severed tube, and a single 105 control for the chuck, the cutter, the center and the dislodging member. 110

4. A machine for forming coupling ends for flexible tubing including rotatable hollow work gripping means to receive the 115 stock therethrough, means disposed beyond the work gripping means to engage the stock to allow the latter to be cut to predetermined lengths, means to support the end of the stock projected beyond the work 120 gripping means, cutting means, and means to move the gripping means, the cutting means and the supporting means to operative and inoperative position. 125

5. A machine for forming coupling ends 130

- for flexible tubing comprising a rotary chuck, a cutter movable toward and from the same to act on a projecting length of tube, a withdrawable center acting to support the projecting end of the tube while being severed, and means for simultaneously rendering the chuck, the cutter and the center inoperative.
6. A machine for forming coupling ends for flexible tubing comprising a rotary chuck, a cutter movable toward and from the same to act on a projecting length of tube, a withdrawable center acting to support the projecting end of the tube while being severed, means for simultaneously rendering the chuck, the cutter and the center inoperative, a dislodger for removing the severed length of tube rendered operative by said means during the inoperative disposal of the other elements.
7. A machine for forming coupling ends for flexible tubing comprising a rotary chuck, a cutter movable toward and from the same to act on a projecting length of tube, a tail stock having a part forming a gage stop for the tube fed from the chuck, a center slideable through the stop part for entering and supporting the projecting end of the tube, and means for simultaneously rendering the cutter and center inoperative and vice versa.
8. A machine for forming coupling ends for flexible tubing comprising a rotary chuck, a cutter movable toward and from the same to act on a projecting length of tube, a tail stock having a part forming a gage stop for the tube fed from the chuck, a center slideable through the stop part for entering and supporting the projecting end of the tube, an operating lever, a movable bar supporting the cutter and controlled by the lever, and a connection between the lever and center for withdrawing the latter upon rendering the cutter inoperative.
9. A machine for forming coupling ends for flexible tubing comprising a rotary chuck, a cutter movable toward and from the same to act on a projecting length of tube, a tail stock having a part forming a gage stop for the tube fed from the chuck, a center slideable through the stop part for entering and supporting the projecting end of the tube, an operating lever, a movable bar supporting the cutter and controlled by the lever, a dislodger mounted to move across the path of the center for removing a severed length of tube, and means for simultaneously operating the dislodger and withdrawing the center upon movement of the lever to inoperatively dispose the cutter.
10. A machine for forming coupling ends for flexible tubing comprising a rotary chuck, a cutter movable toward and from the same to act on a projecting length of tube, a tail stock having a part forming a gage stop for the tube fed from the chuck, a center slideable through the stop part for entering and supporting the projecting end of the tube, an operating lever, a movable bar supporting the cutter and controlled by the lever a dislodger mounted to move across the path of the center for removing a severed length of tube, means connecting the bar to the chuck for rendering it inoperative when the cutter is withdrawn from operative position, and means for simultaneously operating the dislodger and withdrawing the center upon movement of the lever to inoperatively dispose the cutter.
11. A machine for forming coupling ends for flexible tubing including rotatable hollow work gripping means to receive the stock therethrough, means disposed beyond the work gripping means to engage the stock to allow the latter to be cut to predetermined lengths, means to support the end of the stock projected beyond the work gripping means, cutting means, work dislodging means, and means to move the gripping means, the cutting means and the supporting means to inoperative position and simultaneously to move the dislodging means to operative position.
12. A machine for forming coupling ends for flexible tubing including rotatable hollow work gripping means to receive the stock therethrough, means to support the end of the stock projected beyond the work gripping means, a stop for engaging the work through which the supporting means is movable, cutting means, and means to simultaneously move the work gripping means, the cutting means and the supporting means into and out of operative position.
13. A machine for forming coupling ends for flexible tubing including rotatable hollow work gripping means to receive the stock therethrough, means to support the end of the stock projected beyond the work gripping means, cutting means, work dislodging means, and means for simultaneously moving the work gripping means, the cutting means and the supporting means into and out of operative position.

In testimony whereof I have signed my name to this specification in the presence of two subscribing witnesses.
